UNITED STATES PATENT OFFICE.

ROBERT R. WEAVER, OF COLUMBUS, OHIO, ASSIGNOR TO THE RALSTON STEEL CAR COMPANY, OF COLUMBUS, OHIO.

CAR UNDERFRAME.

Specification of Letters Patent.

Patented Feb. 1, 1916.

1,170,129.

Application filed June 15, 1915. Serial No. 34,174.

To all whom it may concern:

Be it known that I, ROBERT R. WEAVER, a citizen of the United States, and a resident of Columbus, in the county of Franklin and State of Ohio, have invented certain new and useful Improvements in Car-Underframes; and I do hereby declare the following to be a full, clear, and exact description of the invention, such as will enable others skilled in the art to which it appertains to make and use the same.

This invention relates to improvements in car underframes,—one object of the invention being to provide a simple underframe to which the body of the car may be applied without cutting away a considerable portion of the same.

A further object is to provide a substantial steel end sill extending from side sill to side sill for the body end to rest against.

A further object is to provide a simple end sill construction which will form a buffer for the car body.

With these and other objects in view, the invention consists in certain novel features of construction and combinations of parts as hereinafter set forth and pointed out in the claims.

In the accompanying drawings, Figure 1, 30 is a plan view of a portion of a car underframe, showing an embodiment of my invention; Fig. 2 is a longitudinal section of the same on the line 2—2 of Fig. 1; Fig. 3 is an enlarged partial plan view of the end sill structure and its connection with a side sill; Fig. 4 is a front elevation of the structure shown in Fig. 3; Fig. 5 is a plan view of a portion of the end sill channel; Fig. 6 is a transverse sectional view through the central portion of the end sill structure, showing the position occupied by the body end sill; Fig. 7 is a detail view of one of the gussets for connecting the end sill with the side sills; Fig. 8 is a transverse sectional view through the end sill at one of the end posts; and Fig. 9 is a fragmentary plan view, partly in section, of the structure shown in Fig. 8.

1, 1, represents the center girder members 50 of a car underframe, and 2, 2, the side sills. The depth of the center girder is reduced gradually from the center of the underframe to points rearwardly of the car bolsters, and those portions 3 of said center girder which 55 are disposed over the trucks of the car (not

shown) are of shallow approximately uniform depth. The reduced portions 3 of the center girder, are connected with the side sills by bolster members 4, 4. A cover plate 4^a is secured over and connects the upper flanges of center girder members and extends approximately from end to end of the latter, and a wide cover plate 5 extends from bolster member to bolster member and from side sill to side sill of the car underframe,—said wide cover plate being riveted to the bolsters, the side sills and the center girder.

At each end of the underframe, the forward ends of the center girder members are recessed as shown at 6, for the accommodation of my improved end sill structure, (hereinafter described in detail) and these recessed end portions of the center girder members may be formed, by means of center girder extensions 7 secured to the main center girder members somewhat below the plane of the tops of the latter and projecting forwardly beyond the same. In view of this dropping of the forward ends of the center girder members, the bottom angle beams of the latter will be dropped somewhat, as shown at 8.

My improved end sill comprises a steel end sill channel 9 which extends across the depressed center girder extension, and is disposed with its flanges projecting rearwardly. The respective ends of the end sill channel are curved rearwardly, as shown at 10, Figs. 3 and 5, and terminate near the forward ends of the side sills. The end sill structure also comprises a sheet metal member 11 secured at its outer edge to the upper flange of the end sill channel 9, from which it extends rearwardly as shown at 12; then downwardly as shown at 13; and then rearwardly as shown at 14, the portion 14 being seated at its center on the depressed center girder extension. In this manner a box-shaped end sill structure, open at its bottom, 100 is formed and extends from side sill to side sill of the underframe.

The steel box or hollow end sill structure is connected at its ends to the ends of the side sills by means of gussets 15, such as 105 shown in Fig. 7. Each of these gussets is secured to the end portion of a side sill, and has portions which extend under the lower horizontal portion 14 of the end sill sheet 11 and under the end sill channel 9, to both 110

of which it is securely riveted. That portion of the end sill structure over the rear horizontal member 14 of the end sill sheet and the vertical member 13 thereof, forms a 5 pocket in which the wooden end sill 16 of the car body is seated. Thus my improved end sill structure affords an end seat for the car body, from side sill to side sill, and permits the body to be readily placed in 10 position,—no other tie than the bolts which held it to the underframe being necessary. It will be observed also that my improved steel end sill constitutes an abutment for the body end sill, and that both are in the 15 same plane.

The top horizontal portion 12 of the end sill structure is slotted as shown at 17 for the accommodation of end post or stiffeners 18 for the end of the car body, and the upper 20 flange of the end sill channel 9 is notched, as at 19, for the same purpose. Each post 18 extends downwardly into the box end sill structure and its lower end is secured between anchoring angles 20 secured to a 25 plate 21, the latter extending transversely under the end sill structure and riveted to the lower flange of the channel 9 thereof and to the rear member 14 of the sheet 11. Similar anchoring angles 22 are secured 30 upon the top member 12 of the end sill structure and to respective sides of the end posts.

Various slight changes might be made in the details of construction of my invention 35 without departing from the spirit thereof or limiting its scope and hence I do not wish to restrict myself to the precise details herein set forth.

Having fully described my invention what 40 I claim as new and desire to secure by Letters Patent, is:—

1. The combination with the side sills of a car underframe, of an end sill structure comprising a member disposed forwardly of 45 the ends of the side sills and projecting above the horizontal plane thereof and having rearwardly extending end portions secured to the side sills, and a plate member comprising an upper horizontal portion secured 50 to the upper edge of the first mentioned end sill member, a lower horizontal

portion connected with the side sills and a vertical portion connecting said upper and lower horizontal portions.

2. The combination with the side sills of a 55 car underframe, of an end sill structure comprising an end sill channel projecting beyond the ends of the side sills and having its ends connected with the latter, a plate member having an upper horizontal part 60 secured to the top of the end sill channel, a lower horizontal part disposed between the side sills and secured thereto, and a vertical part connecting said upper and lower horizontal parts, and plates secured to the 65 bottom of the end sill channel and to the lower horizontal part of the plate member of the end sill structure.

3. The combination with the side sills and center girder of a car underframe, of an 70 end sill channel having rearwardly turned end portions, a plate secured at its outer edge to the upper edge of said end sill channel and comprising a horizontal member, a vertical member and a lower horizontal 75 member, the latter mounted on the center girder and extending from one side sill to the other, and means securing the ends of said plate and the ends of the end sill channel to the side sills.

4. The combination with the side sills of a car underframe, of an end sill structure extending from one side sill to the other, said end sill structure comprising an end sill channel, and a plate comprising a top horizontal member secured to the top of the end sill channel, a vertical member and a bottom horizontal member, said top member having slots to receive end posts, anchor angles secured upon the top member of said 85 plate, transverse plates secured under the end sill channel and the lower horizontal member of said plate, and post anchors secured to said transverse plates and located within the end sill structure.

In testimony whereof, I have signed this specification in the presence of two subscribing witnesses.

ROBERT R. WEAVER.
